UNITED STATES PATENT OFFICE

2,202,584

MINING APPARATUS

Morris P. Holmes, Claremont, N. H., assignor to
 Sullivan Machinery Company, a corporation of
 Massachusetts

Application June 18, 1935, Serial No. 27,212
 Renewed September 15, 1939

33 Claims. (Cl. 262—28)

This invention relates to mining apparatus, and more particularly to improvements in coal mining apparatus of the combined cutting and loading type.

An object of this invention is to provide an improved coal mining apparatus of the combined cutting and loading type having improved means for cutting and dislodging the coal from the face of a coal seam, and for loading the broken-down coal. Another object is to provide an improved cutting and loading apparatus having improved means for cutting and dislodging the coal and for loading the broken-down coal, the cutting means being supported and actuated in an improved manner. A further object is to provide in an apparatus of the above character improved cutting means for cutting simultaneously a series of superimposed parallel kerfs in a coal seam to form a series of relatively thin, horizontal cores, which break down by their own weight and by the action of the cutters thereon. Yet another object is to provide in a novel manner at the opposite sides of a conveying means a pair of simultaneously-acting cutting devices swingable horizontally toward the conveying means for cutting and breaking down the coal and for moving with a horizontal sweeping action the broken-down coal onto the conveying means. A further object is to provide an improved core-cutting means for cutting simultaneously a series of parallel, relatively thin cores in a coal face whereby the cutting action of the cutting means on the coal effects disruption of the cores from the coal seam. A still further object is to provide a pair of cutting and breaking-down devices pivotally mounted at the opposite sides of a conveying means and swingable horizontally toward the conveying means for cutting simultaneously a series of parallel, superimposed kerfs in the mine wall to form a series of relatively thin, parallel, horizontal cores between the kerfs, for breaking down the cores by the action of the cutters thereon as the devices swing horizontally inwardly, and for moving with a horizontal sweeping action the broken-down coal onto the conveying means. Another object is to provide an improved adjustable supporting and guiding structure for the cutting devices whereby the latter may be adjusted into different elevated cutting positions, together with improved means for swinging the cutting devices about their pivots and for feeding the cutting devices toward the coal face. These and other objects of the invention will, however, hereinafter more fully appear.

In the accompanying drawings there is shown

for purposes of illustration one form which the invention may assume in practice.

In these drawings:

Fig. 1 is a plan view of the illustrative form of the improved mining and loading apparatus, parts being shown in horizontal section to illustrate structural details.

Fig. 2 is a rear end, elevational view of the mining and loading apparatus shown in Fig. 1, a portion of the casing being broken away to illustrate portions of the parallel, superimposed core cutters.

Fig. 3 is a view in longitudinal vertical section taken substantially on line 3—3 of Fig. 1, with the core cutter device swung into its longitudinal position.

Fig. 4 is a view in longitudinal vertical section taken substantially on line 4—4 of Fig. 1,

Fig. 5 is an enlarged plan view showing the swinging, guiding and elevating means for one of the core cutting devices, a portion of the mechanism being shown in horizontal section to illustrate details of construction.

Fig. 6 is a cross-sectional view taken substantially on line 6—6 of Fig. 5.

Fig. 7 is a detail vertical sectional view taken substantially on line 7—7 of Fig. 5.

Fig. 8 is a diagrammatic view showing the improved fluid system and associated control means.

In this illustrative embodiment of the invention there is shown a coal mining apparatus of the combined cutting and loading type for cutting and breaking down the coal from the face of a coal seam and for loading the broken-down coal. The mining apparatus shown is of the floor type, adapted to rest upon and slide over the mine floor during its operation, although it will be evident that if desired the apparatus may be wheel-mounted and track-guided or crawler-tread-mounted and guided, and that various features of the improved apparatus may be embodied in mining apparatus of various other types.

In this illustrative construction there is shown a heavy, massive base 1, herein in the form of a sliding bottom skid support of fabricated construction, herein preferably built up of sheet metal plates suitably secured together as by welding, thereby to form a sliding base frame unit having a smooth bottom surface 2 adapted to rest upon and slide over the mine floor. Mounted centrally on the sliding base unit or bottom skid plate structure is an elevating and loading conveyor 3, while arranged on the sliding base at

55 45 50 55

the opposite sides of the conveyor are core cutting and breaking-down devices, generally designated 4 and 5. The forward portion of the sliding base between the core cutting and breaking-down devices is formed with relatively inclined deflecting side plate portions 6 and 7 converging along a front, transversely extending, penetrating edge 8 for facilitating penetration of the broken-down coal as the apparatus is advanced toward the coal face, the inclined deflecting plates 6 and 7 directing the broken coal toward the forward portion of the conveyor 3, and the latter gathering the broken coal and conveying it rearwardly over the top of the apparatus to a suitable point of disposal. The means for advancing the apparatus along the coal face as cutting and loading progresses, in this instance comprises a pair of hydraulic cylinders 10, 10 arranged in parallel, longitudinally extending relation at opposite sides of the conveyor within the bottom portion of the sliding base structure, each cylinder having a front head 11 secured to the bottom plate of the base frame and a rear head 12 secured to the vertical rear wall plate of the sliding base frame, and each of these cylinders containing a piston 13 having a rearwardly projecting piston rod 14 extending through a packed opening in the rear cylinder head 12. As shown most clearly in Fig. 4, the rear ends of the feed piston rods 14, 14 are secured at 15 to a shoe 16 engageable with the mine floor and having pivotally mounted thereon at 17 an adjustable screw jack 18. The screw jack 18 is adjustable into engagement with the mine roof for securing the shoe 16 in a stationary position against the mine floor, thereby to provide reactance means for the feed pistons. When hydraulic pressure is supplied to the forward end of the feed cylinders 10, the sliding base frame and the devices supported thereby are moved bodily forwardly over the mine floor toward the working face of the coal seam. When hydraulic pressure is supplied to the rear ends of the feed cylinders and the jacks 18 are released, the shoes 16 may be slid forwardly over the mine floor toward the sliding base frame into a new feeding position. It will thus be possible by these successive operations to feed the apparatus forwardly in steps over the mine floor.

Now referring to the conveying means, it will be noted that mounted beneath the conveyor 3 within the sliding base frame is a hydraulic motor 20, having fixed to its power shaft 21 a chain sprocket 22 connected by an endless chain 23 to a chain sprocket 24 fixed to a horizontal shaft 25 arranged transversely of and suitably journaled within the base frame. Fixed to the shaft 25 and driven thereby are usual chain sprockets engaging and driving the endless side chains 26 of the conveyor 3, these side chains being guided in suitable channels formed along the sides of a trough-like frame structure 27 supported on the base frame. Secured to certain chain blocks of the endless side chains are transverse scraper bars 28 adapted to move along a bottom plate 29 secured to the sides of the frame structure 27 and these scraper bars are adapted to engage the broken-down coal adjacent the forward penetrating edge of the sliding base and move the broken coal over the bottom conveyor plate 29 to discharge at the rear end of the trough-like frame 27. It will thus be seen that as the apparatus is advanced toward the coal face as cutting progresses, the broken-down coal is penetrated by the penetrating edge 8 of the sliding base and

directed inwardly by the deflecting plate portions 6 and 7 onto the conveyor, whereby the broken coal is moved rearwardly over the top of the sliding base to a suitable point of disposal.

The improved core cutting and breaking-down devices 4 and 5 are herein of substantially identical construction, and therefore a detailed description of one unit will suffice for both. Referring more particularly to the core cutting and breaking-down unit 4, it will be noted that supported by vertical side plates 32 and 33, secured to the bottom plate of the sliding base and forming portions of the latter and secured to the inner sides of these vertical plates, are parallel, vertical guide members 34, 34, each having a vertical guideway 35 in which is slidably guided for vertical movement a guide member 36, this member in turn having a vertical guideway 37 in which is slidably guided a vertical guide 38 formed integral with a vertically adjustable frame 39 of the core cutting and breaking-down device. It will thus be seen that the guide members 35 and 36 have telescopic relation with respect to the guide members 34, thereby to provide a vertical double telescopic guiding means for the vertically adjustable frame 39. Movement of the guide members 36 with respect to the guide members 34 is limited by stop pins 40 projecting within vertical slots 41 formed in the members 36, and vertical movement of the guides 38 with respect to the guide members 36 is limited by similar stop pins 42 projecting within vertical slots 43 formed in the members 36. Secured to the forward portion of the vertically adjustable frame 39 are rigid arm-like bar hanger supports 44 and 45, these supports projecting horizontally forwardly of the frame 39, and each having formed on its forward extremity a cylindrical bearing portion 46. Each of these cylindrical bearing portions 46 supports a bearing on which are rotatably supported cylindrical bearing portions 47 of a pair of bar hanger frames 48 and 49. Arranged between these bar hanger frames is a pair of bar hanger frames 50 and 51, swivelly mounted on the supporting frames 44 and 45, as will later be described. In this illustrative construction, rigidly secured to horizontal parallel portions of the hanger frames 48, 49, 50 and 51, as by bolts 52, is a series of parallel, superimposed, elongated plane cutter bars 53, herein preferably five in number, arranged in closely spaced relation, and guided about the margin of each of these plane cutter bars is an endless cutter chain 44. The mechanism for driving the cutter chains to circulate the same rapidly about the margins of their respective cutter bars comprises a motor 55 supported within the vertically adjustable frame 39 and having its power shaft 56 horizontally disposed and extending longitudinally of the apparatus. Connectible by a sliding clutch 57 to the forward end of the motor power shaft is an alined shaft 58, and keyed to the forward end of the shaft 58 is a bevel gear 59 having its hub journaled within a bearing supported within the frame 39. The bevel gear 59 meshes with a bevel gear 60 keyed to the lower end of a vertical shaft 61, likewise suitably journaled within the frame 39. Keyed to and driven by the shaft 61 is a double chain sprocket 62 connected through endless drive chains 63 and 64 to sprockets 65 and 66, respectively, keyed to a vertical shaft 67 alined with the pivotal axes of the bar hanger frames. Also keyed to the shaft 67 and driven thereby are chain sprockets 68 engaging and driving the se-

ries of endless cutter chains 54. The cylindrical bearing portions 46 of the supporting frames 44 and 45 support bearings 69 in which are journaled the hubs of two of the chain sprockets, 5 while bifurcated portions of the hanger frames 50 and 51 support bearings in which are journaled the drive sprockets 65 and 66 and the centrally located chain drive sprocket 68. The upper bar hanger 48 supports a bearing in which 10 the hub of the upper chain sprocket 68 is journaled. It will thus be seen that the cylindrical bearing portions 46 of the supporting frames and the bearing portions 47 of the hanger frames provide a swivel mounting about which the series 15 of superimposed cutter bars 53 may be simultaneously swung, the cutter bars being swingable about an axis coincident with the axis of the vertical shaft 67. From the foregoing it will be evident that when the clutch 51 is connected, 20 the series of cutter chains 54 may be simultaneously driven irrespective of the angular position of the cutter bars about their pivotal mountings, through the bevel gearing 59, 60, vertical shaft 61, chain and sprocket connections 25 62, 63, 64, the sprockets 65 and 66, vertical shaft 67, and the chain sprockets engaging the endless cutter chains.

Now referring to the mechanism for simultaneously swinging the series of cutter bars about 30 their pivotal mountings, it will be noted that supported by the frame 39 is a pair of single-acting hydraulic cylinders 75, 75 arranged in longitudinal parallel relation at the opposite sides of the frame 39. Each of these cylinders has 35 a bracket-like front head 76 fixed to the frame 39, and a rear head 77, and each contains a reciprocating piston 78 having a rearwardly projecting piston rod 79, these piston rods extending rearwardly through packed openings in the 40 rear cylinder heads 77. Supported on the rear ends of the feed piston rods are brackets 80, on each of which is journaled a sheave 81. A cable 82 is fixed at its ends at 83 to the front feed cylinder heads 76 and passes around the sheaves 81, the cable having its intermediate portion 45 mounted and guided in a cross opening 84 formed in the upper bar hanger 48 and secured midway between its ends to the hanger. A pair of horizontal sheaves 85 are mounted on brackets secured 50 to the frame 39 for guiding the portions of the cable between its point of connection with the hanger 48 and the sheaves 81 carried by the feed piston rods. It will be evident that when 55 hydraulic pressure is supplied to the forward end of one of the cylinders 75, the feed piston may be moved rearwardly to deflect its cooperating portion of the cable 82, thereby to swing simultaneously the series of cutter bars horizontally in one direction about their pivots with respect to the frame 39. By supplying hydraulic 60 pressure to the forward end of the other cylinder the cutter bars may, of course, be swung simultaneously in the opposite direction about their pivots.

65 The improved means for vertically adjusting the frame 39, together with the cutter bars supported thereby, vertically along its guideways with respect to the sliding base frame comprises three hydraulic jacks 87 of the single-acting double telescopic type, two at the forward end of the frame 39 and one at the rearward end thereof, as shown in Fig. 5. Each of these jacks comprises an outer cylinder 88 containing a vertically reciprocable piston 89 having an upstanding tubular piston rod 90 providing a second cyl-

inder 91. Vertically reciprocable in the inner cylinder 91 is a piston 92 having an upwardly projecting piston rod 93 secured at 94 at its upper extremity to a hanger frame 95 secured to the frame 39. The cylinder 87 is provided with 5 a packed upper head 96, while the inner cylinder 90 is provided with a similar packed upper head 97, and the piston rods extend through packed openings in these heads, respectively. When hydraulic pressure is supplied to the lower 10 ends of the outer cylinders 88, the pistons 89 and 92 are moved upwardly within their respective cylinders to move the frame 39, together with the cutter bars supported thereby, into different elevated positions with respect to the sliding base. By trapping the liquid in the lower 15 ends of cylinders the cutter bars may be locked in the desired elevated position.

The means for supplying hydraulic pressure to the various hydraulic devices comprises a motor 100 arranged within the bottom portion of the sliding base, and having its power shaft 101 horizontally disposed and extending longitudinally of the apparatus, the motor 100 being preferably arranged beneath the conveyor 3 in the manner 20 shown in Fig. 4. Keyed to the forward end of the motor power shaft is a spur gear 102 meshing with a spur gear 103 fixed to the drive shaft 104 of a hydraulic pump 105. As illustrated, the pump 105 is arranged in a chamber 105' adapted 25 to contain a supply of liquid, thereby to form a liquid reservoir. As shown diagrammatically in Fig. 8, the pump 105 has its intake connected with the liquid reservoir, and the discharge side of this pump is connected through conduits 106 30 and 107 and a bypass valve mechanism 108 of any suitable design, to a supply conduit 109 connected to a transverse supply passage 110 formed in a valve box 111 and communicating with the lower ends of a series of vertical valve bores 35 112, 113, 114 and 115. Communicating with the upper ends of these valve bores is a transverse discharge passage 116 formed in the valve box and connected by a discharge conduit 117 to the reservoir. Contained in the valve bores are rotary 40 control valves 118, 119, 120 and 121, respectively, each having a manual control handle. The rear ends of the horizontal feed cylinders 10 are connected by a conduit 122 to the valve bore 45 114, and the forward ends of the feed cylinders 50 114, and the forward ends of the feed cylinders 55 114, are connected by a conduit 123 to the valve bore 114. The lower ends of the vertical lifting jack cylinders 97 are connected through branched conduits 124 and a conduit 125 to the valve bore 115. The forward ends of the horizontal bar 60 swing cylinders 75 are connected to the valve bore 113 through conduits 126 and 127. The conveyor driving motor 20 is connected through a conduit 128 to the valve bore 112 and through a conduit 129 with the discharge conduit 117. 65 When the valve 118, which controls the supply of hydraulic pressure to the conveyor driving motor 20, is in the position shown in Fig. 8, hydraulic pressure may flow from the pump through supply conduit 109, supply passage 110, 65 a passage on the valve 118, and conduit 128, to the supply chamber of the motor, the motor exhaust being connected through the conduit 129 to the discharge conduit 117. When the valve 119, which controls the supply of hydraulic pressure 70 to the horizontal swing cylinders for the cutter bars, is in the position shown in Fig. 8, hydraulic pressure may flow through the supply conduit 109, supply passage 110, a passage on the valve 119, and conduit 126, to the two inner cyl- 75

inders 75, while the two outer cylinders are connected through conduit 121, a passage on the valve 119, discharge passage 116, and discharge conduit 117, to the reservoir. When the valve 120, which controls the supply of hydraulic pressure to the feeding cylinders 10, is in the position shown in Fig. 8, hydraulic pressure may flow through supply conduit 109, supply passage 110, a passage on the valve 120, and conduit 122, to the rear ends of the feed cylinders, while the forward ends of the feed cylinders are connected through conduit 123, a passage on the valve 120, discharge passage 116, and discharge conduit 117, to the reservoir. When the valve 121, which 10 controls the supply of hydraulic pressure to the lifting jack cylinders, is in the position shown in Fig. 8, hydraulic pressure may flow through supply conduit 109, supply passage 110, a passage on the valve 121, and conduits 125 and 124. When 15 the valve 118 is rotated into its closed position, the supply of liquid pressure to the conduit 123 is cut off, thereby interrupting the motor drive. When the valve 119 is turned into its reverse position, the conduit 127 is connected to the supply passage 110, while the conduit 126 is connected to the discharge passage 116. When the 20 position of the valve 120 is reversed, the conduit 123 is connected to the supply passage 110, while the conduit 122 is connected to the exhaust passage 116. When the position of the valve 121 is reversed, the supply of hydraulic pressure from the supply passage 110 to the conduit 125 is cut off, and the conduit 125 is connected to the exhaust passage 116. It will be evident that the 25 valves 119, 120 and 121 may be turned into their closed position to trap the liquid in the cylinders respectively controlled thereby. If desired, the conduits leading to the cutter swing and elevating cylinders may be provided with individual valves so that the cutters may be independently 30 swung and elevated.

Secured as shown in Fig. 1 to the forward portion of the sliding base frame at the opposite sides of the latter are vertical, laterally projecting, deflecting plates 130 for retaining the cuttings and broken-down coal in advance of the sliding base as the apparatus is advanced toward the coal face. These plates are braced, respectively, on the outer vertical walls of the sliding base by diagonal brace members 131. If desired, these deflector plates, instead of being rigidly secured to the sliding base frame, may be bolted to the hanger frames for the cutter bars so that as the cutter bars swing about their pivots the deflector plates move therewith to sweep the broken-down coal toward the conveyor. It will further be evident that, instead of securing the deflector plates 130 rigidly to the sliding base frame, the outwardly projecting lateral portions thereof may be pivotally mounted 50 on the sides of the base frame to swing horizontally inwardly with respect thereto, thereby to enable these deflector plates to be swung or folded inwardly against the sides of the sliding base when in their inoperative position, and the diagonal brace members 131 may of course be 55 made detachable.

The mode of operation of the improved cutting and loading apparatus is as follows: The apparatus is fed bodily over the mine floor toward the coal face by the hydraulic cylinders 10, and these hydraulic cylinders may be employed during maneuvering of the apparatus from one working place to another in an obvious manner. 70 When the apparatus is located adjacent the

working face of a coal seam, as shown in Fig. 1, the core cutting and breaking-down bars are swung to their outermost position with the bars projecting at substantially right angles from the sides of the sliding base frame, as shown in Fig. 5 1. Hydraulic pressure may then be supplied to the feed cylinders to feed the sliding base frame forwardly toward the working face to sump the cutting portions of the cutter bars within the coal. When the sumping cut is completed, hydraulic pressure may be supplied to the bar swing cylinders to swing the bars simultaneously horizontally about their pivots through substantially 180° from the full line position shown in Fig. 1 to the dotted line position shown in that figure. 15 The sliding base frame may, if necessary, during this horizontal swinging operation, be jacked down by any suitable means, not shown, such as jack-pipes or mechanical or hydraulic jacks. As such a procedure is well known, details are not 20 illustrated. As the cutter bars are sumped in and swung horizontally, the series of cutter chains cut parallel superimposed kerfs in the coal to form relatively thin parallel cores, and as cutting progresses the cutters acting on the coal break down the cores, and as the cutter bars are swung the cutter chains act to move with a horizontal sweeping action the broken-down coal onto the conveyor by which the coal is conveyed rearwardly of the apparatus to a suitable point of disposal, such as on a face conveyor or in a mine 30 car. The core cutting and breaking-down devices cut out completely the coal seam to provide an opening sufficiently large so that as cutting progresses, the apparatus moves within the opening created by the cutting devices. When it is desired to vary the elevation of the core cutting and breaking-down bars, with respect to the mine floor, hydraulic pressure may be supplied to the elevating jacks to move the bars from their 35 lowermost position to their elevated position. 40

As a result of this invention, it will be noted that an improved cutting and loading apparatus is provided having improved means for cutting and breaking down the coal in a coal seam and for loading the broken-down coal. It will further be noted that an improved core cutting and breaking-down means is provided for cutting simultaneously a series of superimposed horizontal kerfs in the coal to form a series of relatively thin parallel, horizontal cores between the kerfs, the action of the cutters on the coal disrupting the cores, causing the latter to break down as cutting progresses. It will further be evident that by mounting the cutting and breaking-down means to swing horizontally about parallel, vertical axes at opposite sides of the conveyor, the coal is cut and broken down and the broken-down coal is moved with a horizontal sweeping action onto the conveyor in an improved manner. Further, by the provision of vertical adjusting means for the core-cutting and breaking-down devices, it is possible to cut out completely coal seams of varying height. Other uses and advantages of the improved mining apparatus will be clearly apparent to those skilled in the art. 55

While I have in this application specifically described one form which my invention may assume in practice, it will be understood that this form of the same is shown for purposes of illustration, and that the invention may be modified and embodied in various other forms without departing from its spirit or the scope of the appended claims. 70

What I claim as new and desire to secure by Letters Patent is:

1. In a cutting and loading apparatus, a portable base, a conveyor mounted centrally on said base, vertical guideways on said base at the opposite sides of said conveyor, core cutting means mounted in said guideways at the opposite sides of said conveyor for cutting simultaneously a series of superimposed parallel kerfs in the coal of a coal seam to form a series of superimposed parallel cores between the kerfs, and means for bodily adjusting said core cutting means vertically along said guideways.

2. In a cutting and loading apparatus, a portable base, a conveyor mounted centrally on said base, vertical guideways on said base at the opposite sides of said conveyor, core cutting means mounted in said guideways at the opposite sides of said conveyor for cutting simultaneously a series of superimposed parallel kerfs in the coal of a coal seam to form a series of superimposed parallel cores between the kerfs and for breaking down the cores, and means for bodily adjusting said core cutting means vertically along said guideways.

3. In a cutting and loading apparatus, a portable base, a conveyor mounted centrally on said base, vertical guideways on said base at the opposite sides of said conveyor, core cutting means mounted in said guideways at the opposite sides of said conveyor for cutting simultaneously a series of superimposed parallel kerfs in the coal of a coal seam to form a series of superimposed parallel cores between the kerfs, for breaking down the cores and for moving the broken down coal with a horizontal sweeping action onto said conveyor, and means for bodily adjusting said core cutting means vertically along said guideways.

4. In a cutting and loading apparatus, a portable base, conveying means on said base, and a pair of core cutting and breaking down means mounted on said base at the opposite sides of said conveying means to swing horizontally relative thereto and embodying means for forming simultaneously a series of superimposed, relatively thin, horizontal cores in a coal seam, the cutting action of said cutting means on the coal of itself breaking down said relatively thin cores as said cutting means is swung horizontally.

5. In a cutting and loading apparatus, a portable base, conveying means on said base, and core cutting and breaking down means mounted on said base at one side of said conveying means to swing horizontally relative thereto and embodying means for cutting simultaneously a series of superimposed horizontal kerfs in a coal seam to form a series of superimposed horizontal cores between the kerfs, and means for swinging each of said cutting means from a right angle position at the side of said base through 180° to a right angle position in advance of said conveying means.

6. In a cutting and loading apparatus, a portable base, conveying means mounted centrally on said base, a pair of core cutting means mounted on said base at the opposite sides of said conveying means to swing horizontally relative thereto and embodying means for cutting simultaneously a series of superimposed horizontal kerfs in a coal seam to form a series of superimposed horizontal cores between the kerfs, and means for swinging each of said core cutting means from a right angle position at one side of said base through 180° to a position wherein said core

cutting means is disposed in an opposite right angle position in advance of said conveying means.

7. In a cutting and loading apparatus, a portable base, conveying means mounted centrally on said base, hydraulic cylinders mounted on said base at the opposite sides of said conveying means for feeding said base toward the coal face, vertical guideways on said base at the opposite sides of said conveying means, kerf cutting means mounted on said guideways for vertical adjustment relative to said base, hydraulic cylinders for vertically adjusting said kerf cutting means along said guideways, said kerf cutting means each comprising a kerf cutter swingable horizontally about a vertical axis, and hydraulic cylinders for swinging said kerf cutters about their respective pivotal axes.

8. In a cutting and loading apparatus, a portable base, conveying means mounted centrally on said base, cutting means on said base at the opposite sides of said conveying means each including a kerf cutter swingable horizontally about a vertical axis located on said base in advance of said conveying means, said kerf cutters being swingable from right angle positions at the outer sides of the base each through 180° to an opposite right angle position in advance of said conveying means, and means for swinging said kerf cutters about their respective pivotal axes.

9. In a cutting and loading apparatus, a portable base, conveying means thereon, core cutting and dislodging means mounted for pivotal movement on said base in advance of said conveying means for cutting simultaneously a series of superimposed parallel kerfs in the coal of a coal seam to form a series of superimposed parallel cores between the kerfs and for dislodging the cores as cutting progresses, and means for swinging said core cutting and dislodging means about its pivot through substantially 180° to a position in advance of said conveying means, said cutting and dislodging means moving the dislodged coal with a sweeping action onto said conveying means.

10. In a cutting and loading apparatus, a portable base, conveying means thereon, core cutting and dislodging means mounted to swing horizontally in an arcuate path about a vertical axis located on said base in advance of said conveying means for cutting simultaneously a series of superimposed parallel horizontal kerfs in the coal of a coal seam to form a series of superimposed horizontal cores between the kerfs and for dislodging the cores as cutting progresses, and means for swinging said core cutting and dislodging means about its pivot through an angle of substantially 180° to a position in advance of said conveying means, said cutting and dislodging means moving the dislodged coal with a horizontal sweeping action onto said conveying means.

11. In a cutting and loading apparatus, a portable base, conveying means on said base and a pair of cutting and breaking down means mounted on the base at the opposite sides of said conveying means to swing horizontally relative thereto and embodying means for forming simultaneously a series of superimposed horizontal cores in a coal seam, and means for swinging said cutting and breaking down means about their pivots each through an angle of substantially 180°.

12. In a cutting and loading apparatus, a portable base, conveying means on said base, and a pair of core cutting and breaking down means mounted on the base at the opposite sides of said

conveying means to swing horizontally relative thereto and embodying means for forming simultaneously a series of superimposed horizontal cores in a coal seam, and means for swinging said cutting and breaking down means about their pivots through an angle of substantially 180° from positions wherein the core cutting and breaking down means extend at right angles from the sides of said base to opposite right angle positions in advance of said conveying means.

13. In a cutting and loading apparatus, a portable base, conveying means on said base, a pair of core cutting and breaking down means mounted on the base at the opposite sides of said conveying means to swing horizontally relative thereto and embodying means for forming simultaneously a series of superimposed horizontal cores in a coal seam, means for swinging said cutting and breaking down means about their pivots each through an angle of substantially 180°, and means for adjusting said core cutting and breaking down means vertically relative to said base.

14. In a cutting and loading apparatus, a portable base, conveying means on said base, a pair of cutting and breaking down means mounted on the base at the opposite sides of said conveying means to swing horizontally relative thereto and embodying means for forming simultaneously a series of superimposed horizontal cores in a coal seam, means for swinging said cutting and breaking down means about their respective pivots, each through an angle of substantially 180°, from positions wherein the core cutting and breaking down means extend at right angles from the sides of said base to opposite right angle positions in advance of said conveying means, and means for adjusting said core cutting and breaking down means vertically relative to said base.

15. In a cutting and loading apparatus, core cutting means for forming an opening in a coal seam of such size as to provide clearance for the apparatus as the latter is advanced toward the coal face and embodying a pair of cooperating relatively movable core cutting devices each for cutting simultaneously a series of superimposed, relatively closely spaced, parallel kerfs in the coal to form a series of superimposed, relatively thin, parallel cores between the kerfs, the cutting action of the cutting devices on the coal of itself breaking down the relatively thin cores as cutting progresses.

16. In a cutting and loading apparatus, a portable base, a conveyor mounted on said base, vertical guideways on said base, core cutting means mounted in said guideways and including a series of superimposed horizontal endless chain kerf cutters for cutting simultaneously a series of superimposed parallel kerfs in the coal of a coal seam to form a series of superimposed parallel cores between the kerfs, and means for bodily adjusting said core cutting means vertically along said guideways.

17. In a cutting and loading apparatus, a portable base, a conveyor mounted on said base, vertical guideways on said base, core cutting means mounted for bodily vertical adjustment along said guideways and also pivotally mounted for horizontal swinging movement relative to said guideways for cutting simultaneously a series of superimposed parallel kerfs in the coal of a coal seam to form a series of superimposed parallel cores between the kerfs, for breaking down the cores and for moving the broken down coal with a horizontal sweeping action onto said conveyor,

and means for bodily adjusting said core cutting means vertically along said guideways.

18. In a cutting and loading apparatus, a portable base, a conveyor mounted centrally on said base, vertical guideways on said base at the opposite sides of said conveyor, core cutting means mounted in said guideways at the opposite sides of said conveyor for cutting simultaneously kerfs in the coal of a coal seam to form cores, and means for bodily adjusting said core cutting means vertically along said guideways.

19. In a cutting and loading apparatus, a portable base, a conveyor mounted centrally on said base, vertical guideways on said base at the opposite sides of said conveyor, core cutting means mounted in said guideways at the opposite sides of said conveyor for cutting simultaneously kerfs in the coal of a coal seam to form cores and for breaking down the cores, and means for bodily adjusting said core cutting means vertically along said guideways.

20. In a cutting and loading apparatus, a portable base, a conveyor mounted centrally on said base, vertical guideways on said base at the opposite sides of said conveyor, core cutting means mounted in said guideways at the opposite sides of said conveyor for cutting simultaneously kerfs in the coal of a coal seam to form cores, for breaking down the cores and for moving the broken down coal with a horizontal sweeping action onto said conveyor, and means for bodily adjusting said core cutting means vertically along said guideways.

21. In a cutting and loading apparatus, a portable base, conveying means mounted centrally on said base, a pair of core cutting means mounted on said base at the opposite sides of said conveying means to swing horizontally relative thereto and each embodying means for cutting simultaneously kerfs in a coal seam to form cores, and means for swinging each of said core cutting means from a right angle position at its respective side of said base through 180° to a position wherein said core cutting means is disposed in an opposite right angle position in advance of said conveying means.

22. In a cutting and loading apparatus, a portable base, conveying means mounted centrally on said base, hydraulic cylinders mounted on said base at the opposite sides of said conveying means for feeding said base toward a coal face, kerf cutting means mounted at the opposite sides of said conveying means for adjustment in a vertical direction relative to the base, hydraulic cylinders, individual to the kerf cutting means at the opposite sides of the conveying means, for elevating said kerf cutting means, said kerf cutting means each comprising a kerf cutter swingable horizontally about a vertical axis and hydraulic cylinders for swinging said kerf cutters about their respective pivots.

23. In a cutting and loading apparatus, a portable base, conveying means on said base and a pair of cutting and breaking down means mounted on the base at the opposite sides of said conveying means to swing horizontally relative thereto and embodying means for forming horizontal cores in a coal seam, and means for swinging said cutting and breaking down means about their pivots each through an angle of substantially 180°.

24. In a cutting and loading apparatus, a portable base, conveying means on said base and a pair of cutting and breaking down means mounted

- on the base at the opposite sides of said conveying means to swing horizontally relative thereto and embodying means for forming horizontal cores in a coal seam, and means for swinging 5 said cutting and breaking down means about their pivots each through an angle of substantially 180° from positions wherein the cutting and breaking down means extend at right angles from the sides of said base to opposite right angle positions in 10 advance of said conveying means.
25. In a cutting and loading apparatus, a portable base, conveying means on said base, a pair of core cutting and breaking down means mounted on said base at the opposite sides of said conveying means to swing horizontally relative thereto and embodying means for forming horizontal cores in a coal seam, means for swinging said core cutting and breaking down means about their pivots each through an angle of substantially 180°, and means for adjusting said core cutting and breaking down means vertically relative to said base. 15
26. In a cutting and loading apparatus, a portable base, conveying means on said base, a pair of cutting and breaking down means mounted on the base at the opposite sides of said conveying means to swing horizontally relative thereto and embodying means for forming horizontal cores in the coal seam, means for swinging said cutting 20 and breaking down means about their pivots, each through an angle of substantially 180°, from positions wherein the cutting and breaking down means extend at right angles from the sides of said base to opposite right angle positions in advance of said conveying means, and means for adjusting said core cutting and breaking down means vertically relative to said base. 25
27. In a cutting and loading apparatus, a portable base, core cutting means on said base for 30 forming an opening in a coal seam of such size as to provide clearance for said base as the apparatus is advanced toward the coal face and embodying a pair of cooperating endless chain cutting mechanisms each operative to cut simultaneously a series of superimposed, relatively closely spaced, parallel kerfs in the coal to form a series of superimposed, relatively thin, parallel cores between the kerfs, the cutting action of the cutting means on the coal of itself breaking down the 35 relatively thin cores as cutting progresses.
28. In a cutting and loading apparatus, a portable base, conveying means on said base, and core cutting means on said base for forming an opening in a coal seam of such size as to provide 40 clearance for said base as the apparatus is advanced toward the coal face and embodying pairs of endless chain cutting mechanisms pivotally mounted on said base at the opposite sides of said conveying means, each operative to cut simultaneously a series of superimposed, relatively closely spaced, parallel kerfs in the coal to form a series of superimposed, relatively thin, parallel cores between the kerfs, the cutting action of the cutting means on the coal of itself breaking down 45

the relatively thin cores as cutting progresses, and said cutting mechanisms moving the broken down coal with a horizontal sweeping action onto said conveying means.

29. In a cutting and loading apparatus, a portable base, conveying means on said base, coal cutting and disintegrating means mounted on said base at one side of said conveying means to swing horizontally relative thereto for cutting and breaking down the coal of a coal seam and 10 for moving the broken down coal onto said conveying means, and means for swinging said cutting and disintegrating means from a right angle position at the side of said base through 180° to a right angle position in advance of said conveying means. 15

30. In a cutting and loading apparatus, coal cutting and disintegrating means for forming an opening in a coal seam of such size as to provide clearance for the apparatus as the latter is advanced toward the coal face and embodying a pair of cooperating relatively movable coal cutting and disintegrating devices, each for cutting simultaneously a series of superimposed, relatively closely spaced, parallel kerfs in the coal and 20 for breaking down, solely by the cutting action of such devices, fragments of the relatively thin sections of the coal between the kerfs as cutting progresses. 25

31. In a cutting and loading apparatus, a portable base, a conveyor mounted centrally on said base, vertical guideways on said base at the opposite sides of said conveyor, coal cutting and disintegrating means mounted in said guideways at the opposite sides of said conveyor for cutting and 30 breaking down the coal of a coal seam, and means for bodily adjusting said coal cutting and disintegrating means vertically along said guideways. 35

32. In a cutting and loading apparatus, a portable base, a conveyor mounted centrally on said base, vertical guideways on said base at the opposite sides of said conveyor, coal cutting and disintegrating means pivotally mounted in said guideways at the opposite sides of said conveyor 40 and swingable horizontally relative thereto for cutting and breaking down the coal of a coal seam and for moving the broken down coal with a horizontal sweeping action onto said conveyor, and means for bodily adjusting said cutting and 45 disintegrating means vertically along said guideways. 50

33. In a cutting and loading apparatus, a portable base, conveying means on said base, and a pair of coal cutting and disintegrating means 55 mounted on said base at the opposite sides of said conveying means to swing horizontally relative thereto and embodying means for cutting and breaking down the coal in the coal seam, and means for swinging said cutting and disintegrating means about their pivots each through an angle of substantially 180°. 60

MORRIS P. HOLMES.
